[57] **CLAIM**

The ornamental design for a carrier for a cassette player and cassettes, substantially as shown and described.

DESCRIPTION

FIG. 1 is a perspective view of a carrier for a cassette player and cassettes showing my new design:

FIG. 2 is a reduced scale front elevational view thereof in the extended condition;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.
